UNITED STATES PATENT OFFICE

ADOLPHE C. PETERSON, OF MINNEAPOLIS, MINNESOTA

CONSTANT-COMPRESSION ENGINE

Application filed September 7, 1922. Serial No. 586,796.

My invention relates to internal combustion engines and particularly to an engine having various improved features but in particular a constant compression wherefore it is called a constant compression engine.

The principal objects of my invention are to provide an engine having a constant compression whereby efficiency is secured, to provide an engine which is simple in construction, simple in its valve mechanism, simple in its general construction, simple in its cooling means, silent and durable in operation, which provides large port area, full volumetric efficiency at high speeds, and which in general provides an engine which may be economically constructed, is economical in operation and maintenance.

The principal feature of my engine is a novel form of charging which is provided by a novel valve and flow system.

The principal devices and combinations of devices comprising my invention are as hereinafter described and as defined in the claim.

In the accompanying drawings which illustrate my invention, like characters refer to like parts throughout the several views.

Referring to the drawings:

Figure 1, is a view chiefly in vertical cross section on the line XI—XI of Figures 2 and 3, some parts being broken away and some parts being shown in full side elevation.

Figure 2 is a view chiefly in vertical cross section on the line X²—X² of Figure 1, some parts being broken away and some parts being shown in full side elevation.

Figure 3 is an end view of the engine shown in Figures 1 and 2.

Fig. 4 is an enlarged section of the valve.

Fig. 5 is an enlarged front elevation of the same valve.

Fig. 6 is a detail section of certain conduits.

Referring again to the drawings, the numeral 1 indicates the main casting of the engine, and this casting has formed integrally with it cylinders 2 and has cast end members 3 and a crank chamber bottom 4, which latter has broad sides 5 whereby the bottom 4 forms with the remaining portions of the casting a rigid construction supporting the

other parts and at the same time forms a lubricating reservoir. The casting 1 has thereby a rectangular form in the upper part wherein the cylinders are formed and supported and this rectangular form is squarely cut off on each side so that so-called radiator sides 6 and 7 respectively, may be attached one to each side of the main casting and thereby cover the sides of the crank chamber and also provide a water jacket space 8 extending from the cylinders on each side into radiator reservoirs 9 and 10 respectively formed in the radiator sides 6 and 7. The radiator reservoirs 9 and 10 have air-cooling tubes 11 passing vertically upward through them formed in or welded in the radiator sides as shown.

The radiator sides 6 and 7 are preferably cast of aluminum and constitute not only the radiator reservoirs 9—10 and crank case sides but also contain integrally cast tubes or conduits as hereinafter described whereby when they are secured to the sides of the main casting these conduits together with the conduits or ports cast in the main casting 1 connect all the parts in their working cooperation.

Each cylinder has within it a reciprocable sleeve 12 having a close sliding fit and within the sleeve having a close sliding fit therein a reciprocable piston 13 adapted to drive through related crank rods 14 a crank shaft 15 mounted in ball bearings in the end members 3. The crank shaft 15 through a half-time gear 16—17 drives an eccentric shaft 18 having eccentrics 19 at half the crank shaft speed, each eccentric 19 reciprocating one of the sleeves 12.

A head casting 20 is secured upon the top of the main casting 1 and has depending cylindrical heads 21, one depending into each cylinder, between which and the cylinder bore the upper end of the related sleeve 12 slides with a close fit whereby compression may be maintained in the cylinder. The head casting 20 has also integrally formed gas-charge chambers 22, one for each cylinder formed in the center of the related head 21 immediately above the compression space of the cylinder 2. Each gas-charge chamber 22 has a port 23 at its lower end delivering into the cylinder

bore and at its upper end has a port 24. The ports 24 of the two cylinders are controlled by a small reciprocating piston valve 25 which is reciprocated by a rod 26, bell-crank 27 and eccentric rod 28 by an eccentric 29 rotated by eccentric shaft 18. A fuel pump piston 33 is reciprocated through a connecting rod also by bell-crank 27.

The piston 33 pumps liquid fuel from a conduit 34 and delivers at high pressure through a spray nozzle into a mixing chamber 35 which receives air from a conduit 36 as hereinafter described, and delivers the mixture of fuel and air as controlled by valve 25 alternately during the suction or charging strokes of the related pistons into the gas-charge chambers 22. The valve 25 also has an interior passage 37 by which as controlled by valve 38 air only may be delivered into each 20 gas charge chamber as hereinafter described, during a part of the charging stroke.

The head casting 20 has an interior water space or conduit which receives water as pumped by a centrifugal pump 39 and discharges through a small central aperture 40 in each depending head around the gas charge chamber into individual water return passages 41 in each head whereby the cooling water is circulated in part through each head 30 and returned to the water space 8. The water pump 39 is driven by a chain sprocket wheel 42 by chain 43 by sprocket wheel 44 upon eccentric shaft 18. The shaft 45 of the water pump 39 extends through casting 1 and drives 35 an electric generator 46 mounted upon a shelf 47 formed integrally with casting 1.

The crank shaft 15 has mounted upon it at one end an air blower 48 placed in a chamber 49 formed by main casting 1 and in the side 40 castings 6-7 and this air blower receives air from the atmosphere and delivers under low pressure in several streams as follows. The main stream of air normally flows through a port 50 into two branch conduits 51-52 (see 45 Figure 2) which pass respectively through the side castings 6-7 and each delivers into an individual air chamber 53 from which the individual air stream flows in many smaller streams through the tubes 11 of the related 50 air-chamber 53 into separate air-conduits 54. The air conduits 54 direct an air stream adjacent to and past a port 55 in the related cylinder into an air conduit 56 which then delivers into one of the two common exhaust conduits 55, 57 or 58. Each cylinder thus has two ports 55, one on each side, and as described has related to the port 55 on one side an air-passage constituted by the air conduits 54, 56 of that side and has related to the port 55 on its 60 other side an air-passage constituted by the air-conduits 54, 56 of that side. For each cylinder there is thus a related passage on each of its two sides adapted to conduct an individual stream of air adjacent to and past 65 one of its two ports 55. The conduits 51-52

are cast in the main casting 1 and the radiator sides 6-7. The conduits 51-52 in the radiator sides 6-7 join similar conduits in the main casting 1, shown in Figure 3, and extending to a common point or meeting adjacent to port 50, shown in Figure 1. Likewise the exhaust conduits 57-58 are cast in the two radiator sides 6-7 and extend to the opposite end of the main casting 1 into the housing of blower 59. As hereinafter described 70 main casting 1 and radiator sides 6-7 have the conduits so cast in them as to form the connections herein described. The exhaust conduits 57-58 deliver to the interior space of a blower 59 mounted upon and 75 driven by the crank shaft 15 at the opposite end from that on which blower 48 is placed and by this blower 59 the exhaust air and products as hereinafter described are drawn and passed to atmosphere. The two 80 blowers 48 and 59 operate conjointly to produce a continuous and effective blast of air through the air conduits so that under operation there is a constant and strong blast of air through each of the individual passages 85 54-56 past their related ports 55. Either blower 48 or 59 may alone be used for this purpose it being contemplated that the use of the two will produce a more continuous and effective blast.

Each cylinder has in its related sleeve 12 two ports 60 (see Figure 2) each of which in the downward movement of the sleeve is adapted to permit communication between the cylinder through the ports with the two 100 related individual air conduits or passages adjacent to them during a little more than the entire period of the exhaust and suction strokes of the related piston.

The main stream of air as described normally flows through the tubes 11 on its way to the passages 54-56 in streams related to each port 55, but part or all of the main stream may be directed directly into the individual passages 54 from two supplementary 110 air conduits 61-62 each formed in one of the radiator sides 6-7 and each receiving air from the air-blower 48 when a flat valve 63 is moved to direct all or part of the main stream directly into the passages 54 by way 115 of the conduits 61-62, the individual air streams through the passages 54 into the passage 56 past the ports 55 being preserved in either case. The valve 63 may be manually moved and the water temperature thereby 120 controlled, but it is to be noted that this may be done automatically by a thermo-statically controlled means regulating the air flow according to the temperature in the water 125 space 8.

A conduit 64 receiving air also from blower 48 delivers a small stream of air into conduit 36 the air being heated by an electric heating element 65, and conduit 64 also delivers a small stream of air into conduit 37 only 130

when valve 38 is opened in some phases of the operation as hereinafter described. The conduit 37^a provides means whereby, when valve 38 is opened, air may flow from conduit 64 to the housing of the bell-crank 27 and thence to the adjacent end of the valve 25, at which conduit 37 is open as shown in Figure 1. The housing of bell-crank 27 and eccentric rod 28 is a closed housing so this air delivery, which is at relatively low pressure, may be accomplished. The conduit 37 has small ports 37^b at each end which deliver to annular spaces 37^c and 37^d formed in the valve 25.

The crank shaft 15 by means of an eccentric 15 66 drives a lubricating oil piston 67 which reciprocates in an oil lubricating cylinder 68 placed in the bottom 4 and delivering into a conduit 69 which delivers to the central bearing 70 and thence through a conduit 71 to any portion of the engine as is usually done.

A spark plug 72, one in each gas charge chamber 22 receives a spark periodically at the period of or near maximum compression in each cylinder by current from the distributor 73.

It is to be noted that each of the radiator sides 6—7 close one side of the main casting 1 and since all the operating parts are included in interstices in casting 1 which are 30 open at the sides these interior spaces or interstices are all closed when the side members 6—7 are bolted on the main casting and only the operating shafts 15 and 18 and the water pump shaft protrude whereby a closed whole 35 is secured and all the operating parts are readily accessible by removing the side members 6—7. And as certain of the conduits are contained in the side members and cooperate with passages in the main casting these are 40 also joined up properly by the mere attaching of the side members 6—7.

In the operation of my engine, the crank shaft 15 is given initial revolution by any means, as for instance the generator 46 operating as a motor, and when so revolved the blower 48 will draw air from the atmosphere and pass it through the tubes 11 from chambers 53 through each related set of air-conduits 54—56 thereby passing the air stream in 50 separated individual air streams past each port 55 of each cylinder 2. The separated air streams passing by each port 55 into air conduits 56 meet again in the two exhaust conduits 57—58 and the two main streams in the 55 two exhaust conduits 57—58 themselves join in the interior space of the blower 59. The two blowers 48, 59 thereby operate together to induce a continuous and effective blast of air in individual streams through each set 60 of air conduits 54—56 by its related port 55. At each exhaust and succeeding charge period of a cylinder 2 the related ports 55 will be simultaneously uncovered by their common sleeve 12 of the particular cylinder 2 and in 65 the first or exhaust portion the cylinder will

exhaust into the air stream passing by the ports 55 and during the succeeding suction or charge stroke of the piston in that cylinder 2 the cylinder 2 will draw air from the passing air stream in air-conduits 54—56 related into the cylinder. While the cylinder is exhausting the pressure of exhaust carries the gas products or combustion products into the passing air stream but the flow through port 55 of the cylinder is reversed as soon as suction is induced by the suction stroke of the related piston. During this proceeding the air blast through the related air conduits 54—56 constantly carries exhaust combustion products with it into the exhaust conduits 57—58 so that as soon as the reversal of flow occurs there is fresh air flowing past the ports which fresh air is then induced to enter the cylinder.

A minor air stream flows from blower 48 through mixing chamber 35 where it will constantly receive fuel sprayed in a fine spray into it and from the fuel pump and the gas mixture formed will then as controlled by the piston valve 25 periodically pass into each gas charge chamber 22. This charging of gas mixture into the gas charge chamber 22 will occur during the suction stroke of the related piston in cylinder 2. The volume of air drawn into each chamber 22 during its charging period will depend upon the extent of opening of valve 38 which is manually controlled.

The volume of fuel delivered from piston 33 will depend upon the extent to which the by-pass shown in connection with the fuel pump piston 33 and conduit 34 in Figure 1 is opened by the hand valve shown and thereby delivery of fuel may be proportioned to the load. The delivery of air with the fuel from the chamber 35 to gas charge chambers 22 will depend on the extent of the opening of the hand valve shown on conduit 36 and this should be so manually controlled that in relatively light loads a small volume of air will pass and thereby 100 all or most of the fuel charge will not be expelled or drawn under suction from chamber 22 and so that at heavy loads a relatively large volume of air may pass and thereby 105 some of the periodic fuel charge may be carried out of the chamber 22 into the main combustion chamber or cylinder through port 23. The extent to which the fuel charge in the chamber 22 discharges from that chamber into the main space of the cylinder will 110 depend upon the volume of air which enters the chamber 22 from conduit 36 and thereby 115 the degree of commingling of the fuel mixture in chamber 22 with the main body of air is controlled.

Under some conditions, as maximum load, the valve 38 may be opened whereby some pure air charge may be admitted from the housing of bell-crank 27 and may be admitted to the chamber 22 immediately after 120 125

the gas charge during the same suction stroke whereby a still further mixing of the fuel and air charge is secured in the main compression space A. Under all conditions maximum compression is maintained in the cylinders at compression periods as the air charge through the ports 55 is never restricted and under all conditions at maximum compression just before ignition or near that period some of the air charge or air and fuel charge 10 as the case may be will be forced from the compression space A into the chamber 22 causing turbulence and mixing of the charge in chamber 22, on account of the restricted flow through the port between the chamber 15 22 and the cylinder space. As the air and fuel charges in chambers 22 are thereby controlled according to the load conditions ignition is always certain irrespective of the load, because under light load conditions a rich 20 air and fuel mixture is retained in the chamber 22 at the ignition period. It is to be noted that the control of the air charge to chambers 22 may be either wholly by the control of the air charge entering through conduit 36 by valve 36A in conduit 36 or by other 25 means.

The water cooling means by tubes 11 is shown merely incidentally in connection with 30 the air charging means as an efficient utilization of the air-charging stream for cooling in addition, but it is to be noted that the cooling by means of the passing of the air charging stream through the tubes 11 may 35 be omitted and any other cooling means used.

It is to be noted that the principal feature of my engine is the passing of the individual air streams through each set of air conduits 40 54-56, by each port 55, by means of blowers 48-59 or either of these blowers so that there is an independent current of air passing by each port 55 for carrying off the exhaust of the port 55 during exhaust period and for delivering fresh air to the port 55 during 45 the port's suction period. The fuel charging by the minor air stream through the mixing chamber 35 is an incidental feature of the charging system but this fuel charging may be accomplished by any other known 50 means.

While I have shown particular detailed devices and combinations of devices in the illustration of my invention I contemplate that other detailed devices and combinations 55 of devices may be used in the realization of my invention without departing from the spirit and contemplation thereof.

What I claim is:

In a constant-compression engine of the 60 sleeve-valve type having a cylinder and co-operating piston therein, a passageway in the cylinder block adjacent the bore thereof, a port between said passageway and said bore, blower-actuated means to cause a continuous 65 air stream through said passageway and past

said port, a sleeve valve governing said port and controlling the alternate expulsion of exhaust gas from said cylinder into said air stream and the admission from said air stream of scavenging air and additional mixture air for use in the ensuing fuel charge for the engine through said port, said fuel charge being admitted through an independently valve-controlled port into the combustion chamber of the engine. 70

In witness whereof I have hereunto set my hand this 9th day of September, 1921.

ADOLPHE C. PETERSON.
